UNITED STATES PATENT OFFICE

124,610

DESIGN FOR A DISPLAY BOX OR SIMILAR CONTAINER

Edward M. Norton, Dunellen, N. J., assignor to N & W Manufacturing Corp., Dunellen, N. J.

Application March 29, 1940, Serial No. 91,333

Term of patent 14 years

To all whom it may concern:

Be it known that I, Edward M. Norton, a citizen of the United States, residing at Dunellen, county of Middlesex, and State of New Jersey, have invented a new, original, and ornamental Design for a Display Box or Similar Container, of which the following is a specification, reference being had to the accompanying drawing forming part thereof.

I claim:

The ornamental design for a display box or similar container, substantially as shown.

EDWARD M. NORTON.
